UNITED STATES PATENT OFFICE.

JOHN S. RAYNOR, OF PHILADELPHIA, PENNSYLVANIA.

CLIP FOR FASTENING EXPANDED-METAL LATHS.

Application filed May 7, 1924. Serial No. 711,521.

To all whom it may concern:

Be it known that I, JOHN S. RAYNOR, a citizen of the United States, residing at Philadelphia, in the county of Philadelphia 5 and State of Pennsylvania, have invented new and useful Improvements in a Clip for Fastening Expanded-Metal Laths, of which the following is a specification.

My invention relates to new and useful 10 improvements in a clip for fastening expanded metal laths and wire woven laths to plasterers' steel furring irons or bars, and has for its object to provide an exceedingly simple and effective device of this description 15 which will give a hundred per cent efficiency in fastening such laths to such bars by securing the laths to the bars throughout the entire length of the latter.

A further object of my invention is to so 20 construct this clip that it may be properly used by persons of little or no skill and will be fool-proof when applied.

Another object of my invention is to so construct and apply the clip that a better 25 surface for the plasterer's trowel will be provided when applying the first or scratch coat of plaster.

A still further object of my invention is to so construct these clips that during the application 30 thereof one after the other will overlap and lock the preceding clip so that by securing the free end of the last clip in the series a whole series will be securely locked in place against any possibility of 35 displacement.

With these ends in view, this invention consists in the details of construction and combination of elements hereinafter set forth and then specifically designated by the 40 claims.

In order that those skilled in the art to which this invention appertains, may understand how to make and use the same, I will describe its construction in detail, referring 45 by numerals to the accompanying drawing forming a part of this application, in which:—

Fig. 1, is a perspective of a clip made in accordance with my invention.

Fig. 2, is a similar view showing a portion 50 of a plasterer's iron and a woven wire lath attached thereto by my improved clips.

Fig. 3, is a view similar to Fig. 2 showing the locking end of the clip in the position 55 it will assume just prior to locking it upon the plasterer's iron.

In carrying out my invention as here embodied, 1 represents the body of the clip which may be formed of round, square or flat lengths of metal rod, or wire and from 60 this body portion projects a leg 2 at approximately right angles thereto and this leg has a right angle or horizontal section 3 and a down turned section 4 which as a unit forms a locking leg for the purpose hereinafter 65 set forth.

At the opposite end of the body is formed a leg 5 also approximately at right angles thereto and this leg terminates in the right angle or horizontal section 6, this leg and 70 section constituting a stay leg.

7 represents a plasterer's furring iron or bar which is utilized in present day building for the support of metal laths and the plaster carried by the latter and 8 represents a 75 metal lath such as woven wires secured to the bar 7 by a series of my improved clips.

In practice the metal laths 8 are temporarily secured against the bars 7 and first 80 the locking leg of one of the clips is passed through an opening in the lath and turned in cork-screw fashion until the locking leg rests over on top of the bar 7, as clearly shown in Fig. 3, after which the body of the clip is swung parallel with the bar which 85 will swing the section 4 of the locking leg downward to the opposite side of the bar thereby locking it in place and during this swinging of the body the stay leg 5 is passed through one opening in the lath and forced 90 upward so that the section 6 thereof will spring over the top of the bar, as clearly shown in Fig. 2.

The locking leg of a second clip is then 95 passed through an opening in the lath behind the stay leg and brought into locked position as before described and when its stay leg is finally passed through an opening in the lath and sprung into place over the bar a stay leg of the preceding clip will 100 be securely locked in place as will be readily understood by reference to Fig. 2.

This process is continued until a series of clips extending the entire length of the bar 7 have been put in place, the stay leg 105 of the last clip being secured against accidental displacement by wiring or otherwise, thus giving the metal lath a hundred per cent support throughout the entire length of the bar.

Heretofore metal laths have been secured 110 to the furring bars by threading a short

section of wire through the meshes thereof and passing said wire around the bar and then twisting its ends together. This not only requires considerable skill to produce 5 the proper results but only supports the metal lath at intervals leaving it with a tendency to sag and also leaving the twisted ends of the tie wires as an obstruction to the first application of the plaster coat.

- 10 All of these disadvantages are entirely overcome by my invention permitting a much better class of work to be produced by unskilled labor than as to have been produced by skilled labor and rendering it impossible 15 for the improper securement of the lathes to the furring bars.

As before stated the clip may be made of a length of wire or rod of any cross section but in practice I have found that a stiff 20 round steel rod is preferable for this class of work.

Of course I do not wish to be limited to the exact details of construction as herein shown as these may be varied within the 25 limits of the appended claims without departing from the spirit of my invention.

Having thus fully described my invention, what I claim as new and useful is:—

1. As a new article of manufacture, a clip 30 for securing metal lathing in place consisting of a body, a locking leg comprising a leg portion at right angles to the body, a right

angle section projecting from said leg portion and a down turned section projecting from said right angle section, and a stay 35 leg including a leg portion at right angles to the body and a right angle section projecting from said leg portion.

2. In combination with a furring bar and metal lathing, a series of clips, each of said 40 clips comprising a body portion coacting with the lathing, a locking leg embracing the bar, and a stay leg supported by said bar, the locking legs of each succeeding clip 45 engaging the body of the preceding one to hold the stay leg of said preceding clip in place against the bar.

3. The combination of a bar and metal lathing coacting therewith, of a plurality 50 of clips, each of said clips including a body in engagement with a portion of the lathing, a locking leg at one end of the body and passing thru the lathing and partway around the bar and across the body of a preceding clip, and a stay leg at the other end of said 55 body and passing thru the lathing and partway around the bar, but a less distance than the locking leg, and held in place by the coaction of the locking leg of a succeeding clip with the body. 60

In testimony whereof, I have hereunto affixed my signature.

JOHN S. RAYNOR.
